FLUIDIC CONTROL SYSTEM OF FUEL INJECTION DEVICE FOR INTERNAL COMBUSTION ENGINES

This invention relates to a control system for a fuel injection device of internal combustion engines which injects fuel directly into the suction manifold of the engine while atomizing the fuel without using a carburetor.

As a fuel injection device of internal combustion engines, there has been used a suction type carburetor which utilizes the vacuum pressure at the Venturi portion in the suction pipe of an engine, a mechanical injection device which injects fuel directly into each cylinder or suction manifold of an engine without using a carburetor of the type described, or an electrical injection device which has electronic means at a fuel controlling portion thereof.

The suction type carburetor mentioned above sucks and discharges fuel by making use of a pressure lowering of the suction gas at a fixed Venturi or variable Venturi. The fixed Venturi type carburetor, as is well known, has the disadvantage that systems for a low speed operation, an intermediate speed operation and a high speed operation must inevitably be separated from each other according to the velocity range of the suction gas flow and a smooth operation of the engine is impaired at the point when the carburetor is connected to each system. On the other hand, the variable Venturi type carburetor can eliminate the above-described disadvantage of the fixed Venturi type, but has the disadvantage that mechanisms for operatively associating a variable fluidic resistance provided in the fuel passage with the variable Venturi, and said variable Venturi with the flow rate of air sucked into the engine, etc., not only call for a precision in machining but also become complicated in construction and large in size, and thus the production cost thereof becomes high.

The mechanical and electronic injection devices are also complicated in construction and high in production cost, and therefore, are rarely used for internal combustion engines other than those which are used for special applications.

The first object of the present invention is to provide a control system which controls a fuel injection device of internal combustion engines in such a manner that an adequate quantity of fuel as demanded by the engine can be supplied to the engine continuously from a low speed operation to a high speed operation of the engine.

The second object of the invention is to provide a control system which is simple in construction, easy to manufacture and capable of operating the fuel injection device of the internal combustion engine with high accuracy.

The third object of the invention is to provide a control system which controls the fuel injection device in such a manner that, in a high speed, high load region of the engine, fuel is injected continuously except for a very short period of time corresponding to the pulse interval, and as a result, enables the capacity of a pump to be reduced which delivers the fuel to fuel injecting portions with pressure.

The fourth object of the invention is to provide a control system which controls the fuel injection device in such a manner that an optimum quantity of fuel

which has been compensated according to an atmospheric pressure change, is supplied to the engine.

The fifth object of the invention is to provide a control system for the fuel injection device, which comprises a multi-element as a fluidic control circuit and an electrically operated compressor as a source of compressed air for said element, and the function of which will not be impaired even if compressed air is supplied during stoppage of the engine.

According to the present invention, there is provided a control system for a fuel injection device of internal combustion engines, which comprises trigger pulse generating means for generating a trigger pulse in synchronism with the rotation of an internal combustion engine, variable circuit-length means by which the length of a fluid passage can be varied according to the load on said engine and fluidic control circuit for generating a fluidic pulse of a variable width and a variable number in cooperation with said variable circuit-length means and said trigger pulse generating means, the trigger pulse generated by said trigger pulse generating means being applied to said fluidic control circuit and said variable circuit-length means, whereby a fluidic pulse is generated by said fluidic control circuit, which is used for controlling the quantity of fuel supplied to said engine.

FIG. 1 is a diagram showing, partially in section and partially schematically, a first embodiment of the control system according to the invention as applied to an internal combustion engine;

FIG. 2 is a longitudinal cross-sectional view showing in an enlarged scale the variable circuit-length (fluid flow) device shown in FIG. 1;

FIGS. 3a through 3f are diagrams showing the waveforms of pulses generated at various portions of the control systems in the first through fourth embodiment, respectively;

FIG. 4 is a diagram showing the relationship between the pressure in the suction manifold of the internal combustion engine and the delay time of the pulses, under different atmospheric pressures, in the first through fourth embodiment;

FIG. 5 is a view showing, partially in section and partially schematically, the second embodiment of the control system according to the invention as applied to an internal combustion engine;

FIG. 6 is a view showing, partially in section and partially schematically, the third embodiment of the control system according to the invention as applied to an internal combustion engine;

FIG. 7 is a view showing, partially in section and partially schematically, the fourth embodiment of the control system according to the invention as applied to an internal combustion engine;

FIG. 8 is a transverse cross-sectional view of the variable circuit-length device of the fourth embodiment;

FIG. 9 is a diagram showing the relationship between the absolute pressure in the suction manifold of the internal combustion engine and the pulse delay time in the fourth embodiment;

FIG. 10 is a diagram showing the relationship between the absolute pressure in the suction manifold of the internal combustion engine and the quantity of fuel to be supplied to the engine for each revolution thereof, in the fourth embodiment;

FIG. 11 is a view showing, partially in section and partially schematically, a fifth embodiment of the control system according to the invention as applied to an internal combustion engine;

FIG. 12 is a transverse cross-sectional view of the variable circuit-length device for the compensation of the atmospheric pressure, in the fifth embodiment;

FIGS. 13a through 13f are diagrams showing the waveforms of pulses generated at various portions of the control system in the fifth embodiment, respectively;

FIG. 14 is a diagram showing the relationship between the absolute atmospheric pressure and the pulse delay time when the plunger of the variable circuit-length device moves, in the fifth embodiment; and

FIG. 15 is a diagram showing the relationship between the absolute pressure in the suction manifold of the internal combustion engine and the quantity of fuel to be supplied to the engine for each revolution thereof, under different atmospheric pressures, in the fifth embodiment.

The present invention will be described on five embodiments thereof sequentially as applied to an internal combustion engine mounted on a vehicle, such as an automotive vehicle, with reference to the accompanying drawings:

FIGS. 1 and 2 show the first embodiment of the present invention. In these figures, reference numeral 1 designates a compressed air pump driven from an internal combustion engine or electric motor; 2 an air pressure regulating valve by which the pressure of the air discharged from the compressed air pump 1 is maintained constant; 3 a fluidic control circuit; 4 a fluidic multivibrator element consisting of a fluidic flip-flop element; 4a the power supply port of said element; 4b, 4c the control ports of said element; and 4d, 4e the output ports of said element. Reference numeral 5 designates a variable circuit-length device and 5a designates a cylinder of said variable circuit-length device which has a helical groove 5b and an elongate groove 5c formed independently in the inner surface thereof. Reference numeral 5d designates a power supply port communicating with one end of said helical groove 5b and also with the output port 4d of the multivibrator element 4. The pitch of the helical groove 5b is made smaller at the end portion remote from the power supply port 5d. Reference numeral 5e designates an output port of the variable circuit-length device 5, which communicates with said elongate groove 5c and also with the control port 4b of the multivibrator element 4. Reference numeral 5f designates a plunger axially slidably disposed in the cylinder 5a; 5g an annular port formed in the peripheral surface of the plunger 5f at a portion opposed by the helical groove 5b; 5h a port formed in the peripheral surface of said plunger 5f at a portion opposed by the elongate groove 5c; and 5i a passage formed in said plunger 5f and communicating said ports 5g, 5h with each other. Reference numeral 5j designates a power cylinder formed axially of the cylinder 5a integrally therewith and 5k designates a diaphragm disposed in said power cylinder 5j and dividing the interior of said power cylinder into a negative pressure chamber 5e and an atmospheric pressure chamber 5m. The negative pressure chamber 5e is communicated with the suction manifold of the engine

through a negative pressure introducing pipe 5n for introducing the manifold vacuum pressure thereinto, while the atmospheric pressure chamber 5m is communicated with the atmosphere through a communication port 5o. The diaphragm 5k and the plunger 5f are connected with each other by a bolt 5p. Further, the diaphragm 5k is urged toward the atmospheric pressure chamber 5m by a spring 5q disposed in the negative pressure chamber 5e. Reference numerals 6a, 6b, 6c, 6d each designate a fixed fluidic resistance consisting, for example, of an orifice. Reference numeral 7 designates a fluidic monostable multivibrator element having a power supply port 7a, a control port 7b and output ports 7c, 7d. The output port 7c is communicated with the control port 4c of the multivibrator element 4 and the other output port 7d is opened into the atmosphere. Reference numeral 7' designates another fluidic monostable multivibrator having a power supply port 7'a, a control port 7'b and output ports 7'c, 7'd. The output port 7'c is communicated with a compressed air nozzle 25 to be described later. The arrangement is such that when a signal from the output port 4e of the multivibrator element 4 is applied to the control port 7'b of the monostable multivibrator element 7', a signal equivalent to a signal generated at the output port 4d of said multivibrator element 4 is amplified and appears at the output port 7'c of the monostable multivibrator element 7'. At the output port 7'd is generated a signal of a phase exactly reverse to that of the signal generated at the output port 7'c but this signal is released into the atmosphere. Reference numeral 8 designates a fluidic detector for detecting the rate of rotation of the engine 9, which generates an air pulse signal synchronized with the rotation of said engine. The detector 8 includes a rotary body 10 and a member 11 abutting against said rotary body 10. The rotary body 10 rotates at the same rate as that, for example, of the cam shaft of the internal combustion engine 9 and makes one revolution on two revolutions of the crank shaft. Further, the rotary body 10 has circumferential grooves 11c, 11d formed at portions of the peripheral surface thereof and generates one pulse Pa_1 as shown in FIG. 3a on every revolution of the crank shaft. The member 11 has a power supply port 11a and an output port 11b formed therein toward the peripheral surface of the rotary body 10. The output port 11b is communicated with the control port 7b of the monostable multivibrator element 7. The detector 8 generates one output air pulse at its output port 11b only when the communication between the power supply port 11a and the output port 11b is established by each of the grooves 11c, 11d of the rotary body 10, and therefore, generates two air trigger pulses in each revolution of said rotary body 10. The compressed air pump 1 and the air pressure regulating valve 2 supply a constant pressure of compressed air to each of the power supply port 4a of the multivibrator element 4, the power supply ports 7a, 7'a of the monostable multivibrator elements 7, 7' and the power supply port 11a of the detector 8, and the pressure ratio of the compressed air supplied to said respective ports is adjusted by the fixed fluid resistances 6a, 6b, 6c.

Reference character A_1 generally indicates the internal combustion engine 9 and devices associated with said engine, such as a fuel tank 29, a float chamber 28,

etc., which will be described hereunder: Reference numeral 14 designates a cylinder of the engine 9, 15 a piston, 16 an intake valve, and 17 an exhaust valve. Reference numeral 18 designates an intake passage communicating with the intake valve 16, 19 a suction manifold connected to the intake passage 18, and 20 a throttle valve provided in the downstream side of the suction manifold 19. Reference character I₁ generally indicates a fuel injecting portion, in which reference numeral 21 designates a hood of a fuel injection chamber, 22 the fuel injection chamber, 23 a fuel injection nozzle projecting into said chamber 22, and 24 a tubular fuel receiving pipe projecting into the chamber 22. The fuel injection nozzle 23 and the fuel receiving pipe 24 are arranged in opposed relation to each other with a certain distance therebetween and substantially axially aligned with each other. Reference numeral 25 designates a compressed air nozzle projecting into the fuel injection chamber 22, with the axis thereof extending at right angles to a line connecting the tip ends of the fuel injection nozzle 23 and the fuel receiving pipe 24. A fuel return passage 26 has one end connected to the fuel receiving pipe 24, with the other end leading into the float chamber 28. Reference numeral 29 designates a fuel tank and 30 designates a pump by which fuel F in said fuel tank 29 is supplied into said float chamber 28 with pressure, 31 a fuel injection pump and 31a a battery constituting a power source for said pump 31. Reference numeral 32 designates a pressure regulating valve by which the discharge pressure of the pump 31 is maintained constant. The fuel F in the float chamber 28 is set to the fuel injection nozzle 23 at a predetermined pressure and a predetermined flow rate by the pressure regulating valve 32 and the fuel injection pump 31. Reference numerals 33a, 33b designate cam shafts to open and close the intake valve 16 and exhaust valve 17 respectively. Reference numeral 34 designates a negative pressure sensing port opened into the suction manifold 19 at a point downstream of the throttle valve 20 and communicating with the negative pressure introducing pipe 5n of the variable circuit-length device 5. The plunger 5f of the variable circuit-length device 5 and the throttle valve 20 operatively connected by a link mechanism 35 through a switching device 42 which operates on a special occasion, so that said plunger 5f may be operated on the special occasion according to the degree of opening of said throttle valve 20. The output port 7'c of the multivibrator element 7' is communicated with the compressed air nozzle 25. Reference numeral 36 designates a valve which senses an abrupt deceleration of the engine by way of the manifold vacuum pressure from the negative pressure sensing port 34 and interrupts the air pulse signal supplied from the detector 8 to the control port 7b of the monostable multivibrator element 7. Reference numeral 37 designates a valve which detects a malfunction of the compressed air pump 1 by way of presence or absence of the discharge pressure of said pump and interrupt the power supply to the fuel injection pump 31. Reference numeral 38 designates a check valve and 39 designates an air injection nozzle positioned with its axis extending toward the exhaust valve 17 and communicating with the discharge side of the compressed air pump 1. Reference numeral 13 designates an ignition switch of

the vehicle and the fuel injection pump 31 is set in motion when said ignition switch 13 is closed.

The control system of the invention constructed as described above operates in the following manner: 5 Namely, a constant pressure of compressed air is always supplied to the power supply port 4a of the multivibrator element 4, the power supply ports 7a, 7'a of the monostable multivibrator elements 7, 7' and the power supply port 11a of the rate of rotation detector 8 by the compressed air pump 1 and the air pressure regulating valve 2. When the air pulse signal P_{a1} as shown in FIG. 3a, generated at the output port 11b of the detector 8 is applied to the control port 7b of the monostable multivibrator element 7 under such condition, said element 7 generates an air pulse of a width t_{n1} as shown in FIG. 3b, irrespective of the rate of rotation of the engine 9. The air pulse thus generated at the output port 7c is applied as a trigger signal to the control port 4c of the next stage multivibrator element 4, whereupon the compressed air entering the power supply port 4a of said element 4 is directed into the output port 4d and the output from said output port 4d is partially supplied to the power supply port 5d of the 15 variable circuit-length device 5. The compressed air thus introduced into the variable circuit-length device 5 passes at the sonic velocity through a passage formed by the helical groove 5b, the annular port 5b, the passage 5i, the port 5h and the elongate groove 5c, and reaches the output port 5e, with a time delay as determined by the length of said passage. Since the length of the passage 5i is predetermined, the delay time is varied by the length of the helical groove 5b from the power supply port 5d to the annular port 5g (hereinafter referred to as effective length). The plunger 5f constantly moves according to the magnitude of the manifold vacuum pressure introduced into the negative pressure chamber 5e, and further moves on the special occasion according to the degree of opening of the 20 throttle valve transmitted thereto through the link mechanism 35. Now, when the manifold vacuum pressure is introduced into the negative pressure chamber 5e through the negative pressure sensing port 34 and the negative pressure introducing pipe 5n, the diaphragm 5k is attracted toward the negative pressure chamber 5e under the effect of negative pressure against the biasing force of the spring 5q, and accordingly the plunger 5f is moved in the direction of the arrow B₁. The amount of movement of the plunger 5f is proportional to the magnitude of the negative pressure introduced into the negative pressure chamber 5e. Upon movement of the plunger 5f in the direction of the arrow B₁, the annular port 5g is brought into communication with the helical groove 5b. Thus, it will be understood that the effective length of the passage becomes progressively short and hence the delay time becomes progressively small, as the negative pressure in the negative pressure chamber 5e becomes large. On the contrary, the effective length of the passage and, therefore, the delay time becomes progressively long as the negative pressure in the negative pressure chamber 5e decreases. The same operation as described above takes place also in the event when the plunger 5f is moved by the link mechanism 35. The relationship 25 between the pressure P_1 (mmHg) in the suction manifold 19 and the delay time t_a (mm sec) of the

pulse, is shown in FIG. 4. In the diagram of FIG. 4, a curve indicated by reference character E represents the characteristic of the control system when the engine is operated on the horizontal ground where the atmospheric pressure is 760 mmHg. The pitch of the helical groove 5b is made small at the end remote from the power supply port 5d so that the gradient of curve E may be relatively gentle within the range of the pressure in the manifold 19 from 400 to 700 mmHg but may be relatively sharp when the pressure exceeds 700 mmHg. A curve indicated by reference character D represents the characteristic of the control system when the engine is operated on the high ground, such as in the mountains, where the atmospheric pressure is 660 mmHg. As seen, the curve D is the curve E which is displaced to the left parallel to the axis of abscissa by a distance corresponding to 100 mmHg. Reference symbol Max on the axis of ordinate indicates the point where the delay time of the pulse is longest, and Min indicates the point where the delay time is shortest. With the rate of rotation of the engine being constant, when pulses (each of a width of tn_1) delayed, for example, by times t_1 , t_2 , t_3 as shown in FIG. 3c, by the variable circuit-length device 5, are applied to the control port 4b of the monostable multivibrator element 4, the flow of compressed air which has been passing through the output port 4d, is directed into the output port 4e. When the pulse applied to the control port 4b is P_{c_1} shown in FIG. 3c, a compressed air pulse of Pd_1 shown in FIG. 3d is generated at the output port 4d. Similarly, when the pulse is P_{c_2} , a compressed air pulse of Pe_1 shown in FIG. 3e, and when the pulse is P_{c_3} , a compressed air pulse of Pf_1 shown in FIG. 3f, is generated at the output port 4d. The waveform of each pulse is rectangular and the period thereof is t_0 . The widths of the respective compressed air pulses Pd_1 , Pe_1 , Pf_1 are determined by the delay time provided by the variable circuit-length device 5, i.e., the magnitude of the manifold vacuum pressure representing the size of the engine load, and are indicated by t_1 , t_2 , t_3 respectively.

In order to follow the high speed operation of the engine, it is necessary to increase the quantity of fuel supplied during one cycle of operation of the engine to the possible extent, by reducing the pulse interval and increasing the pulse width, even though the period of the pulse is short. If an arrangement is made such that a pulse P_{c_3} is generated when the delay time provided by the variable circuit-length device 5 is t_3 and longest, as shown in FIG. 3f, and the falling point of this pulse becomes equal to the rising point of the output compressed air pulse Pb_1 of the monostable multivibrator element 7, the pulse interval will become shortest and tn_1 and the pulse width will become largest and t_3 . The sum of the maximum value t_3 of pulse width and the minimum value tn_1 of pulse interval is the period of the pulse and this period is determined by the maximum rate of rotation of the engine. Therefore, the time which can be used for injecting the fuel can be made longest, even during the high speed operation of the engine.

At the output port 4e are generated compressed air pulses whose phases are reverse to those of the blown pulses generated at the output port 4d and shown in FIGS. 3d, 3e, 3f, respectively. When the compressed air pulses generated at the output port 4e are applied to

the control port 7'b of the monostable multivibrator element 7', amplified compressed air pulses of the same phases as those of the pulses shown in FIGS. 3d, 3e, 3f are generated at the output port 7'c respectively.

5 Where no compressed air pulses are generated at the output port 7'c of the multivibrator element 7', a jet of fuel injection nozzle 23 flows entirely into the fuel receiving pipe 24 and returned to the float chamber 28 through the fuel return passage 26.

10 However, when a compressed air pulse appears at the output port 7'c of the multivibrator element 7', said compressed air pulse is jettisoned from the compressed air nozzle 25, so that the fuel passing from the fuel injection nozzle 23 into the fuel receiving pipe 24 is deflected and atomized into the suction manifold 19 and the atomized fuel is injected into the cylinder 14 through the throttle valve 20. In order to obtain a suction gas of a predetermined fuel air ratio, it is only necessary to control the ratio between the product of the suction efficiency and the air density (which is proportional to the quantity of air sucked in each cycle of the engine 9) and the pulse width, to be a predetermined value. In the present invention, the fuel air ratio is constantly controlled to be an optimum value by varying the quantity of fuel to be injected, according to the magnitude of the manifold vacuum pressure supplied into the negative pressure chamber 5e of the variable circuit-length device 5 through the negative pressure sensing port 34 and according to the degree of opening of the throttle valve 20 on a special occasion.

15 On the other hand, the compressed air from the compressed air pump 1 is supplied to the air injecting nozzle 39 through the check valve 38 and injected from said nozzle toward the exhaust valve 17. Therefore, the toxic gases, such as carbon monoxide and unburned hydrocarbons, contained in the exhaust gas are oxidized and rendered harmless which they are exhausted through the exhaust valve 17.

20 In decelerating the engine 9 quickly, the valve 36 is actuated to interrupt the air pulse supplied from the rate of rotation detector 8 to the control port 7b of the monostable multivibrator element 7. Therefore, the air flowing into the power supply port 4a of the multivibrator element 4 continuously discharged from the output port 4e, as no air pulses are supplied to the control port 4c. Consequently, no output pulse signals are generated at the output port 7'c of the monostable multivibrator element 7' and the fuel injected from the fuel injection nozzle 23 is entirely received in the fuel receiving pipe 24 to be returned to the float chamber 28. In other words, when the engine 9 is to be quickly decelerated, the fuel supply to the engine is stopped and the discharge of the exhaust gas is also stopped.

25 When the compressed air pump 1 fails, the compressed air pulse is no longer supplied to the compressed air nozzle 25 and therefore, the fuel injected from the fuel injection nozzle 23 is entirely received in the fuel receiving pipe 24 and returned to the float chamber 28. In this case, the fuel is continuously circulated and the fuel vapor is released into the atmosphere during circulation, which is not only dangerous but also causes pollution of the atmosphere. According to the invention, however, the valve 37 is actuated upon failure of the compressed air pump 1, to interrupt the current supply to the fuel injection pump 31 and

thereby interrupt the fuel supply to the fuel injection nozzle 23.

In this embodiment, the signal generated at the output port 4d of the fluidic monostable multivibrator element 4 is amplified by the fluidic monostable multivibrator element 7' and the amplified signal of the same phase is obtained at the output port 7'c of said element 7', as described above. However, it should be understood that the output port 4d of said element 4 may be communicated directly with the air injection nozzle 25 to be described later, without providing the element 7'c, and in this case, the waveform of the pulse reaching the injection nozzle 25 unavoidably becomes deformed and weakened to some extent.

In the first embodiment of the control system according to the present invention which is constructed as described above, the output signal of the fluidic monostable multivibrator circuit passing through the feed back circuit is delayed by a time corresponding to the engine load, by varying the length of the helical passage according to the engine load and then applied to the control port of said monostable multivibrator element. The monostable multivibrator element performs its function depending upon whether the delayed output signal has arrived at the control port or not, and generates a compressed air pulse having a width corresponding to the engine load. In this way, it is possible to supply a quantity of fuel just enough to meet the demand of the engine continuously from a low speed operation to a high speed operation of the engine according to the rate of rotation of said engine. Further, the fluidic monostable multivibrator circuit operates depending upon whether the output signal delayed by the variable circuit-length device has arrived at the control port thereof. Therefore, the multistable operation is highly accurate and fast and the width of the output pulse of the fluidic monostable multivibrator circuit, i.e., the quantity of fuel injected can closely follow the engine load. Another excellent advantage is that a fluctuation of the pulse width can be avoided even if the monostable multivibrator circuit is designed with a certain degree of freedom. Furthermore, according to the instant invention the control system operates highly reliably and the entire system can be provided in a compact form, because the injection of fuel does not directly involve a mechanical moving part and none of the parts associating with the fuel injection particularly call for machining precision, and in addition, the fluidic elements are small in size and can be put together at one location, no additional works being required other than piping. Therefore, the control system of the invention is highly adapted for use with an internal combustion engine of an automobile wherein the available space is particularly limited, makes it possible to prolong the useful life of the engine and can be provided at a low cost.

It should also be noted that, in the present invention, the minimum value of pulse interval of the output compressed air pulse signal of the second fluidic monostable multivibrator element can be reduced to a value equal to the pulse width of the output pulse of the first fluidic monostable multivibrator element. Therefore, by previously setting the output pulse of the first fluidic monostable multivibrator element at a small value, it is possible to make the aforesaid pulse interval very small

and thereby to inject a quantity of fuel demanded by the engine, into the suction manifold continuously and uniformly, not only in the low speed, low load region but also the high speed, high load region of the engine, except for a very short period of time corresponding to the pulse interval. This is very advantageous in that a fuel injection pump of small capacity can be used at the fuel injecting portion and in that the quantity of fuel supplied to the respective cylinders of a multi-cylinder engine can be uniformized.

The second embodiment of the invention will be described hereunder with reference to FIG. 5 in which same parts or devices as those used in the first embodiment are indicated by same reference numerals with 100 added thereto. In FIG. 5, reference numeral 101 designates a compressed air pump driven from an internal combustion engine or an electric motor, 102 an air regulating valve by which the discharge air pressure of said compressed air pump 101 is maintained constant; 103 a fluidic control circuit; and 104 a fluidic monostable multivibrator element having a power supply port 104a, control ports 104b, 104c, 104c', an OR output port 104d and a NOR output port 104e. The output port 104d and the control port 104c are communicated with each other by a pipe 104f for positive feed back, and the output port 104e is opened into the atmosphere. Reference numeral 105 designates a variable circuit-length device which is identical in construction with the variable circuit-length device 5 shown in FIG. 1. A power supply port 105d of the device 105 is communicated with a pipe communicating an output port 107c of a fluidic monostable multivibrator element 107 to be described later and the control port 104c of the monostable multivibrator element 104 with each other, and an output port 105e thereof is communicated with the control port 104b of said element 104. Reference numerals 106a, 106b, 106c, 106d designate fixed fluidic resistances, each consisting, for example, of an orifice, respectively. Reference numeral 107 designates a fluidic monostable multivibrator element having a power supply port 107a, a control port 107b and output ports 107c, 107d. The output port 107c is communicated with the control port 104c of the monostable multivibrator element 4 and the other output port 107d is opened into the atmosphere. Reference numeral 108 designates a fluidic rate of rotation detector which generates an air pulse in synchronism with the rotation of the engine 109. The detector 108 is identical in construction with the detector 8 shown in FIG. 1 and is designed to generate one pulse P_{A_1} shown in FIG. 3a on every revolution of the crank shaft. An output port 111b of a member 111 is communicated with the control port 107b of the monostable multivibrator element 107. The compressed air pump 101 and the air pressure regulating valve 102 supply a constant pressure of compressed air to each of the power supply ports 104a, 107a of the monostable multivibrator elements 104, 107 and the power supply port 111a of the detector 108, and the pressure ratio of the compressed air supplied to said respective ports is adjusted by the fixed fluidic resistances 106a, 106b, 106c.

Reference character A_2 generally indicates the internal combustion engine 109 and devices associated therewith, and the construction of the portion A_2 is ex-

actly identical with that of A₁ in FIG. 1. A compressed air nozzle 125 is communicated with the OR output port 104d of the monostable multivibrator element 104, and a negative pressure sensing port 134 is communicated with a negative pressure introducing pipe 105n of the variable circuit-length device 105. A plunger 105f of the variable circuit-length device 105 and a throttle valve 120 are operatively connected with each other by a link mechanism 135 through a switching device 142 which is operated on a special occasion, so that said plunger 105f may be operated on a special occasion according to the degree of opening of said throttle valve 120. The functions of valves 136, 137 are exactly the same as those of the valves 36, 37 in FIG. 1.

The second embodiment of the invention constructed as described above operates as follows: A constant pressure of compressed air is always supplied to the power supply ports 104a, 107a of the monostable multivibrator elements 104, 107 and the power supply port 111a of the detector 8 by the compressed air pump 101 and the air pressure regulating valve 102. When the air pulse signal Pa₁ shown in FIG. 3a and generated at the output port 111b of the detector 108 on every revolution of the crank shaft is applied to the control port 107b of the monostable multivibrator element 107 as a trigger pulse, under such condition, said element 107 generates the air pulse Pb₁ of a pulse width tn₁ as shown in FIG. 3b, at its output port 107c irrespectively of the rate of rotation of the engine 109. The air pulse generated at the output port 107c is partially supplied as a trigger pulse to the control port 104c of the next stage monostable multivibrator element 104, whereby the compressed air which has been flowing from the power supply port 104a into the NOR output port 104e, is directed into the OR output port 104d. The compressed air discharged from the OR output port 104d is partially supplied to the control port 104c after restricting the flow rate by the fluidic resistance 106d. By so doing, the compressed air continues to flow through the OR output port 104d, even after the compressed air pulse supplied from the output port 107c of the monostable multivibrator element 107 to the control port 104c of the monostable multivibrator element 104 disappears. On the other hand, the compressed air pulse generated at the output port 107c of the monostable multivibrator element 107 is partially supplied to the power supply port 105d of the variable circuit-length device 105. The compressed air pulse thus supplied passes at the sonic velocity through the passage formed by a helical groove 105b, an annular port 105g, a passage 105i, a port 105h and an elongate groove 105c, and reaches the output port 105e with a delay time as determined by the length of said passage. Since the length of the passage 105i is predetermined, the delay time is varied by the length of the helical groove 105b from the power supply port 105d to the annular port 105g (hereinafter referred to as effective length). The effective length of the variable circuit-length device 105 is varied in the following manner: Namely, the plunger 105f constantly moves according to the magnitude of the manifold vacuum pressure introduced into a negative pressure chamber 151, and further moves on a special occasion according to the degree of opening of the throttle valve which is transmitted

through the link mechanism 135. Now, when the manifold vacuum pressure is introduced into the negative pressure chamber 151 through the negative pressure sensing port 134 and the negative pressure introducing pipe 105n, a diaphragm 105k is attracted under suction toward the negative pressure chamber 151 against the biasing force of a spring 105q and accordingly the plunger 105f is also moved in the direction of the arrow B₂. The amount of movement of the plunger 105f is proportional to the magnitude of the negative pressure introduced into the negative pressure chamber 151. Upon movement of the plunger 105f in the direction of the arrow B₂, the annular port 105g is shifted to a position to communicate with the helical groove 105b. Thus, it will be understood that the aforesaid effective length and hence the delay time becomes progressive short as the negative pressure in the negative pressure chamber 151 becomes progressively large, and conversely becomes progressively long as the latter becomes progressively small. The above-described operation similarly takes place when the plunger 105f is moved by the link mechanism 135. The relationship between the pressure P₁ (mmHg) in the suction manifold 119 and the pulse delay time ta (mm sec) is exactly the same as described previously with reference to the first embodiment and as shown in FIG. 4. With the rate of rotation of the engine being constant, when the pulses (each of a width of tn₁) delayed, for example, by times t₁, t₂, t₃ by the variable circuit-length device 105 as shown, for example, in FIG. 3c, are applied to the control port 104b of the monostable multivibrator element 104, the compressed air flow which has been passing through the OR output port 104d, is directed into the NOR output port 104e. Therefore, if the pulse applied to the control port 104b is P_{c1} shown in FIG. 3c, a compressed air pulse of Pd₁ shown in FIG. 3d is generated at the output port 104d, and similarly, if the pulse is P_{c2} or P_{c3}, a compressed air pulse of P_{e1} or P_{f1} shown in FIG. 3e or 3f appears at said port respectively. The widths of the pulses Pd₁, P_{e1}, P_{f1} are the values of t₁, t₂, t₃ which are determined by the delay times provided by the variable circuit-length device 105 or the magnitude of the manifold vacuum pressure representing the size of the engine load, respectively.

In order to follow the high speed operation of the engine, it is necessary to increase the quantity of fuel supplied during one cycle of operation of the engine to the possible extent, by reducing the pulse interval and increasing the pulse width, even though the period of the pulse is short. If an arrangement is made such that a pulse P_{c3} is generated when the delay time provided by the variable circuit-length device 105 is t₃ and longest, as shown in FIG. 3f, and the falling point of this pulse becomes equal to the rising point of the output compressed air pulse Pb₁ of the monostable multivibrator element 107, the pulse interval will become shortest and tn₁, and the pulse width will become largest and t₃. The sum of the maximum value t₃ of pulse width and the minimum value tn₁ of pulse interval is the period of the pulse and this period is determined by the maximum rate of rotation of the engine. Therefore, the time which can be used for injecting the fuel can be made longest, even during the high speed operation of the engine.

At the output port 104e is generated a compressed air pulse of a phase reverse to the air pulse generated at the OR output port 104d but said compressed air pulse is released into the atmosphere.

However, when no compressed air pulses are generated at the OR output port 104d of the monostable multivibrator element 104, the fuel injected from a fuel injection nozzle 123 in the form of a jet flows entirely into a fuel receiving pipe 124 to be returned to a float chamber 128 through a fuel return passage 126.

Now, when a compressed air pulse is generated at the output port 104d of the monostable multivibrator element 104, said compressed air pulse is jettet from a compressed air nozzle 125, so that the fuel passing from the fuel injection nozzle 123 into the fuel receiving pipe 124 is deflected and atomized by said compressed air pulse and injected into the suction manifold 119 to be injected into a cylinder 114 through a throttle valve 120. In order to obtain a mixture of a desired fuel air ratio, it is only necessary to control the ratio between the product of the suction efficiency and the air density (which is proportional to the quantity of air sucked into the engine for each cycle of the engine), and the pulse width, to be a certain value. In this embodiment, the fuel air ratio is controlled to be an optimum value at all times, by varying the quantity of fuel to be injected in accordance with the magnitude of the manifold vacuum pressure introduced into the negative pressure chamber 151 of the variable circuit-length device 105 through the negative pressure sensing port 134, as described above.

As stated above, the rate of rotation detector 108 generates two of the pulse Pa , shown in FIG. 3a during two revolutions of the crank shaft or one cycle of the engine. Therefore, two compressed air pulses are generated at the OR output port 104d of the monostable multivibrator element 104 in each cycle of the engine based on the pulse Pa_1 , and the width of said pulse corresponds to the size of the engine load. Particularly in the high speed, high load region of the engine, the waveform of the compressed air pulse generated at the OR output port 104d becomes close to the waveform shown in FIG. 3f, the pulse width becomes extremely wide and the pulse interval becomes extremely close to the value of tn_1 . Namely, the fuel injected from the fuel injection nozzle 123 for one cycle of engine is almost entirely injected into the suction manifold 119 continuously by the compressed air pulse of an extremely wide width jetted from the compressed air nozzle, except for a short period of time corresponding to the pulse interval, and a very small quantity of fuel injected from the fuel injection nozzle 123 during said short period of time only is returned to the float chamber 128 through the fuel receiving pipe 124. Particularly, in the high speed, high load region of the engine, a quantity of fuel demanded by the engine for one cycle of operation can be continuously uniformly injected into the suction manifold 119 during the period of one cycle, except for the aforesaid very short period of time. This makes it possible to use a pump of smaller capacity for a fuel injection pump 131 than the capacity of the pump required in the case when a quantity of fuel demanded by the engine is injected all at once for only a short period of time during one cycle of the engine. In addition, where the engine is a multi-cylinder engine, the

quantities of fuel to be supplied to the respective cylinders can be uniformized. These advantages are particularly apparent in the high speed, high load region of the engine. Moreover, in the low speed, low load region of the engine, the fuel injection period can be shortened to tn_1 by shortening the pulse delay time to tn_1 , and thereby the quantity of fuel to be injected can be minimized.

10 In this embodiment also, the toxic gases in the exhaust gas are oxidized and rendered harmless by the compressed air blown from an air injection nozzle 139 through a check valve 138; the fuel supply to the engine 109 is interrupted at the time of abrupt deceleration of the engine, by the operation of the valve 136; 15 and the current supply to the fuel injection pump 131 is interrupted by the operation of the valve 137 upon failure of the compressed air pump 101, to interrupt the fuel supply to the fuel injection nozzle 123, as described previously with reference to the first embodiment.

20 In this embodiment, the power supply port 105d of the variable circuit-length device 105 is communicated with the pipe which communicates the output port 25 107c of the monostable multivibrator element 107 and the control port 104c of the monostable multivibrator element 104 with each other, as stated above, but said power supply port 105d may be communicated directly with the output port 104d of said element 104.

30 Because of the construction described above, the second embodiment of the control system has the same effects as those of the first embodiment described previously.

35 An additional advantage of this embodiment is that, since the compressed air pulse generated at the OR output port of the second monostable multivibrator element is supplied to the fuel injecting portion, even if an electrically operated compressor is used for supplying compressed air to said second multivibrator element and compressed air is continuously supplied to said power supply port during the period when the engine is not operated, such compressed air flows into the NOR output port and not into the OR output port, and therefore, gives no detrimental effect on the system at all.

40 The third embodiment of the invention will be described hereunder with reference to FIG. 6 wherein same members or devices as those of the first embodiment shown in FIG. 1 are indicated by the same reference numerals with 200 added thereto, respectively. In FIG. 6, reference numeral 201 designates a compressed air pump driven from an internal combustion engine mounted on a vehicle; 202 an air regulating valve by which the discharge air pressure of said compressed air pump 201 is maintained constant; 203 a fluidic control circuit; and 204 a fluidic bistable multivibrator element consisting of a fluidic flip-flop element and having a power supply port 204a, control ports 204b, 204c, and output ports 204d, 204e. One of the output port 204e is opened into the atmosphere. Reference numeral 205 designates a variable circuit-length device which is identical in construction with the variable circuit-length device 5 shown in FIG. 1. An input port 205d of the variable circuit-length device 205 is communicated with a pipe which communicates an output port 207c of a fluidic monostable multivibrator

tor element 207 to be described later and the control port 204c of the bistable multivibrator element 204 with each other, and an output port 205e thereof is communicated with the control port 204b of said element 204. Reference numerals 206a, 206b, 206c, 206d designate fixed fluidic resistances each consisting, for example, of an orifice. Reference numeral 207 designates a fluidic monostable multivibrator element having a power supply port 207a, a control port 207b and output ports 207c, 207d. The output port 207c is communicated with the control port 204c of the multivibrator element 204 and the other output port 207d is opened into the atmosphere. Reference numeral 208 designates a fluidic rate of rotation detector which generates an air pulse signal in synchronism with the rotation of the engine and is of exactly the same construction as the detector 8 shown in FIG. 1. Namely, the detector 208 generates one pulse P_{a1} shown in FIG. 3a on every revolution of the crank shaft. An output port 211b of a member 211 is communicated with the control port 207b of the monostable multivibrator element 207.

A predetermined pressure of compressed air is supplied by the compressed air pump 201 and the air pressure regulating valve 202 to each of the power supply port 204a of the bistable multivibrator element 204, the power supply port 207a of the monostable multivibrator element 207 and a power supply port 211a of the detector 208, and the ratio of the compressed air pressure supplied to said respective ports is adjusted by the fixed fluidic resistances 206a, 206b, 206c, 206d.

Reference character A_3 generally indicates the engine 209 and devices associated therewith, and the construction of the portion A_3 is exactly the same as that of A_1 shown in FIG. 1. A compressed air nozzle 225 is communicated with the output port 204d of the bistable multivibrator element 204, and a negative pressure sensing port 234 is communicated with a negative pressure introducing port 205n of the variable circuit-length device 205.

A plunger 205f of the variable circuit-length device 205 and a throttle valve 220 are operatively connected by a link mechanism 235 through a switching device 242 which is operated on a special occasion, so that said plunger 205f is moved on a special occasion in accordance with the degree of opening of said throttle valve 220. The functions of valves 236, 237 are same as those of the valves 36, 37 shown in FIG. 1.

Now, the operation of this embodiment of the invention will be described. As stated, a predetermined pressure of compressed air is constantly supplied to each of the power supply port 204a of the bistable multivibrator element 204, the power supply port 207a of the monostable multivibrator element 207 and the power supply port 211a of the rate of rotation detector 208 from the compressed air pump 201 and the air pressure regulating valve 202. When the air pulse signal P_{a1} shown in FIG. 3a and generated at the output port 211b of the detector 208 on every revolution of the crank shaft is applied to the control port 207b of the monostable multivibrator element 207 as a trigger pulse under such condition, an air pulse P_{b1} of a width t_1 as shown in FIG. 3b is generated at the output port 207c of said element 207 irrespectively of the rate of rotation of the engine. The air pulse thus generated at the output port

207c is applied as a trigger pulse to the control port 204c of the bistable multivibrator element 207, whereupon the compressed air flow passing through the power supply port 204a of said bistable multivibrator element 207 is directed into the output port 204d. The air pulse supplied to the control port 204c is partially supplied to a power supply port 205d of the variable circuit-length device 205. The air pulse thus supplied passes at the sonic velocity through a passage 10 formed by a helical groove 205b, an annular port 205g, a passage 205i, a port 205h and an elongate groove 205c, and reaches an output port 205e with a time delay as determined by the length of said passage. Since the length of the passage 205i is predetermined, the 15 delay time is varied by the length of the helical groove 205b from the power supply port 205d to the annular port 205g (hereinafter referred to as effective length). The plunger 205f constantly moves according to the magnitude of the manifold vacuum pressure introduced into a negative pressure chamber 251, and further moves on a special occasion according to the degree of opening of the throttle valve transmitted thereto through the link mechanism 235. Now, when the manifold vacuum pressure is introduced into the negative pressure chamber 251 through the negative pressure sensing port 234 and the negative pressure introducing port 205n, a diaphragm 205k is attracted toward said negative pressure chamber 251 by the effect of vacuum pressure against the biasing force of a spring 205q, and accordingly the plunger 205f moves in the direction of the arrow B_3 . The amount of movement of the plunger 205f is proportional to the magnitude of the negative pressure introduced into the negative pressure chamber 251. Upon movement of the plunger 205f in the direction of the arrow B_3 , the annular port 205g is displaced to a position to communicate with the helical groove 205b. Therefore, the aforesaid effective length and hence the delay time becomes progressively 20 short as the negative pressure in the negative pressure chamber 251 increases, and conversely becomes progressively long as the latter decreases. The same operation as described above takes place also when the plunger 205f is moved by the link mechanism 235. The 25 relationship between the pressure P_1 (mmHg) in the suction manifold 219 and the pulse delay time is as shown in FIG. 4 and exactly the same as previously described with reference to the first embodiment.

With the rate of rotation of the engine being constant, when the pulses delayed by the variable circuit-length device 205, for example, by times t_1 , t_2 , t_3 as shown, for example, in FIG. 3c (the width of the pulses being all t_1) are applied to the control port 204b of the bistable multivibrator element 204, the compressed air flow which has been flowing into the output port 204d, is directed into the output port 204e. Therefore, if the pulse applied to the control 204b is P_{c1} shown in FIG. 3c, a compressed air pulse of P_{d1} shown in FIG. 3d is generated at said output port 204e. Similarly, if the pulse is P_{c2} or P_{c3} , a compressed air pulse of P_{d1} or P_{f1} shown in FIGS. 3e or 3f respectively is generated at said output port 204e, and the widths of said respective pulses P_{d1} , P_{e1} , P_{f1} are the values of t_1 , t_2 , t_3 respectively which are determined by the delay time provided by the variable circuit-length device 205 or the manifold vacuum pressure representative of the size of the engine load.

In order to follow the high speed operation of the engine, it is necessary to increase the quantity of fuel supplied during one cycle of operation of the engine to the possible extent, by reducing the pulse interval and increasing the pulse width, even though the period of the pulse is short. If an arrangement is made such that a pulse P_{C_3} is generated when the delay time provided by the variable circuit-length device 205 is t_3 and longest, as shown in FIG. 3f, and the falling point of this pulse becomes equal to the rising point of the output compressed air pulse P_{b_1} of the monostable multivibrator element 207, the pulse interval will become shortest and t_{n_1} and the pulse width will become largest and t_3 . The sum of the maximum value t_3 of pulse width and the minimum value t_{n_1} of pulse interval is the period of the pulse and this period is determined by the maximum rate of rotation of the engine. Therefore, the time which can be used for injecting the fuel can be made longest, even during the high speed operation of the engine.

At the output port 204e is generated a compressed air pulse of a phase reverse to that of the air pulse generated at the output port 204d, but this pulse is released into the atmosphere.

Where no compressed air pulses are generated at the output port 204d of the bistable multivibrator element 204, the fuel injected from a fuel injection nozzle 223 in the form of a jet flows entirely into a fuel receiving pipe 224 to be returned to a float chamber 228 through a fuel return passage 226.

However, when a compressed air pulse is generated at the output port 204d of the bistable multivibrator element 204, said compressed air pulse is jetted from a compressed air nozzle 225, so that the fuel passing from the fuel injection nozzle 223 into the fuel receiving pipe 224 is deflected and atomized by said compressed air pulse as shown in FIG. 6 and injected into the suction manifold 219 to be injected into a cylinder 214 through the throttle valve 220. When it is desired to obtain a mixture of a desired fuel air ratio, it is only necessary to control the ratio between the product of the suction efficiency and the air density (which is proportional to the quantity of air sucked by the engine during one cycle of the engine), and the pulse width, to be a certain value. In this embodiment, the fuel air ratio is controlled to be an optimum value by varying the quantity of fuel supplied to the engine according to the magnitude of the manifold vacuum pressure supplied into the negative pressure chamber 251 of the variable circuit-length device 205 through the negative pressure sensing port 234, as described above.

As stated above, the rate of rotation detector 208 generates two of the pulse P_{a_1} shown in FIG. 3a during two revolutions of the crank shaft or one cycle of the engine. Therefore, two compressed air pulses are generated at the output port 204d of the monostable multivibrator element 204 in each cycle of the engine based on the pulse P_{a_1} , and the width of said pulse corresponds to the size of the engine load. Particularly in the high speed, high load region of the engine, the waveform of the compressed air pulse generated at the output port 204d becomes close to the waveform shown in FIG. 3f, the pulse width becomes extremely wide and the pulse interval becomes extremely close to the value of t_{n_1} . Namely, the fuel injected from the fuel injection nozzle 223 for one cycle of engine is almost

entirely injected into the suction manifold 219 continuously by the compressed air pulse of an extremely wide width jetted from the compressed air nozzle, except for a short period of time corresponding to the pulse interval, and a very small quantity of fuel injected from said fuel injection nozzle 223 during said short period of time only is returned to the float chamber 228 through the fuel receiving pipe 224. Particularly, in the high speed, high load region of the engine, a quantity of fuel demanded by the engine for one cycle of operation can be continuously uniformly injected into the suction manifold 219 during the period of one cycle, except for the aforesaid very short period of time. This makes it possible to use a pump of smaller capacity for a fuel injection pump 231 than the capacity of the pump required in the case when a quantity of fuel demanded by the engine is injected all at once for only a short period of time during one cycle of the engine. In addition, where the engine is a multi-cylinder engine, the quantities of fuel to be supplied to the respective cylinders can be uniformized. These advantages are particularly apparent in the high speed, high load region of the engine. Moreover, in the low speed, low load region 25 of the engine, the fuel injection period can be shortened to t_{n_1} by shortening the pulse delay time to t_{n_1} and thereby the quantity of fuel to be injected can be minimized.

In this embodiment also, the toxic gases in the exhaust gas are oxidized and rendered harmless by the compressed air blow from an air injection nozzle 239 through a check valve 238; the fuel supply to the engine 209 is interrupted at the time of abrupt deceleration of the engine, by the operation of the valve 236; and the current supply to the fuel injection pump 231 is interrupted by the operation of the valve 237 upon failure of the compressed air pump 201, to interrupt the fuel supply to the fuel injection nozzle 223, as described previously with reference to the first embodiment.

Because of the construction described above, the third embodiment of the control system has the same effects as those of the first embodiment described previously.

The fourth embodiment of the invention will be described hereunder with reference to FIGS. 7 and 8 in which members or devices same as or similar to those included in the first embodiment are indicated by the same reference numerals with 300 added thereto. In FIGS. 7 and 8, reference numeral 301 designates a compressed air pump driven from an internal combustion engine or an electric motor mounted on a vehicle, 302 an air regulating valve by which the discharge air pressure of said compressed air pump 301 is maintained constant, 303 a fluidic control circuit, and 304 a fluidic monostable multivibrator element having a power supply port 304a, control ports 304b, 304c, 304c', an OR output port 304d and a NOR output port 304e. The output port 304d and the control port 304c' are communicated by a pipe 304f for positive feed back, and the output port 304e is opened into the atmosphere. Reference numeral 340 designates a variable circuit-length device having a first casing 340a, and a first helical groove member 340b and a second helical groove member 340c which respectively have helical grooves 340d, 340e formed in the outer peripheral sur-

faces thereof and axial bores 340f, 340g therein. The first and second helical groove members 340b, 340c are axially disposed in said casing 340a in side-by-side relation and their helical grooves 340d, 340e are axially independent of each other, and further, their axial bores 340f, 340g form one through-hole. Reference numeral 340h designates a cylinder body having an axial cylinder bore 340i formed therein. The cylinder body 340h is closely fitted in the axial bores 340f, 340g of the helical groove members 340b, 340c. Reference numeral 340j designates a plunger which is slidably received in the cylinder bore 340i of the cylinder body 340h. Reference numeral 340k designates a second casing which is fixed to the open end of the first casing 340a by bolts 340l and defines a chamber 340m therein. Reference numerals 340n, 340o, 340p, 340q, 340r, 340s designate bellows each made, for example, of a resilient metallic material and having the interior thereof maintained at the absolute pressure of 0 mmHg. These bellows are connected with each other and disposed in the chamber 340m. One of the bellows 340n is connected at its end 340t to the plunger 340j and another one of them 340s is formed with a conical recess 340u at one end thereof, in which is received one end of an adjusting screw 340v. The adjusting screw 340v is threadably screwed into an internally threaded cylindrical portion 340w of the casing 340k. Reference numeral 340x designates a protective cap fitted over the cylindrical portion 340w in threadable engagement with external threads formed in the outer periphery of said portion 340w. Reference numeral 340y designates a spring disposed between the outer end of the cylinder body 340h and one end of the bellows 340n, to surround the plunger 340j. Reference numeral 340z designates a negative pressure introducing pipe which has one end opened in the chamber 340m, with the other end communicating with a negative pressure introducing port 334 which is opened in a suction manifold 319. An arrangement is made such that when the chamber 340m is maintained at a pressure of 760 mmHg, the bellows 340n-340s the interior of which is maintained at the absolute pressure of 0 mmHg, are held in the most contracted state by the manifold pressure and the biasing force of the spring 340y overcomes the resilient forces of said bellows. The pitch of the helical grooves 340d, 340e is made small at the ends closer to the bellows 340n-340s. FIG. 8 is a transverse cross-sectional view of the first helical groove member 340b and the second helical groove member 340c in a plane perpendicular to the axes thereof. As seen, the first and second helical groove members respectively have a plurality of radial passages 341a, 341b extending from the bottoms of the first helical groove 340d and the second helical groove 340e through the bodies of said respective members and the wall of the cylinder body 340h into the cylinder bore 340i, over the entire length of said helical grooves. The plunger 340j has axially spaced first and second annular grooves 341c, 341d formed in the outer peripheral surface thereof for communication with the passages 341a communicating with the first helical groove 340d and the passages 341b communicating with the second helical groove 340e, respectively. These annular grooves 341c, 341d are communicated with each other by a passage 341e formed in the plunger 340j. Reference numeral 341f

designates an output port of the variable circuit-length device 340, which is communicated at one end with the first helical groove 340d at the starting end of the latter, and at the other end with a control port 304b of a fluidic monostable multivibrator element 304 to be described later. Reference numeral 341g designates a power supply port of the variable circuit-length device 340, which is communicated at one end with the starting end of the second helical groove 340e and at the other end with a control port 304c of the monostable multivibrator element 304. Reference numerals 306a, 306b, 306c, 306d designate fixed fluidic resistances each consisting, for example, of an orifice. Reference numeral 307 designates a fluidic monostable multivibrator element having a power supply port 307a, a control port 307b and output ports 307c, 307d. The output port 307c is communicated with the control port 304c of the monostable multivibrator element 304 and the other output port 307d is opened into the atmosphere. Reference numeral 308 designates a fluidic rate of rotation detector which generates an air pulse signal in synchronism with the rotation of the engine 309. The construction of the detector 308 is identical with that of the detector 8 shown in FIG. 1. Namely, the detector 308 is so designed as to generate one pulse P_{a_1} shown in FIG. 3a on every revolution of the crank shaft. An output port 311b of a member 311 is communicated with the control port 307b of the monostable multivibrator element 307. A predetermined pressure of compressed air is supplied by the compressed air pump 301 and the air pressure regulating valve 302 to each of the power supply ports 304a, 307a of the monostable multivibrator elements 304, 307 and a power supply port 311a of the detector 308. The pressure ratio of the compressed air supplied to the respective ports is adjusted by the fixed fluidic resistances 306a, 306b, 306c. Reference character A_4 generally indicates the engine 309 and devices associated therewith, and the construction of the portion A_4 is exactly the same as that of A_1 shown in FIG. 1. A compressed air nozzle 325 is communicated with the OR output port 304d of the monostable multivibrator element 304 and a negative pressure sensing port 334 is communicated with the negative pressure introducing port 340z of the variable circuit-length device 340. The plunger 340j and a throttle valve 320 are operatively connected with each other by a link mechanism 335 through a switching device 342 which is operated on a special occasion, so that said plunger 340j may be operated on a special occasion according to the degree of opening of said throttle valve 320. The functions of valves 336, 337 are exactly the same as those of the valves 36, 37 shown in FIG. 1. The fourth embodiment of the invention constructed as described above operates as follows: As stated above, a predetermined pressure of compressed air is constantly supplied by the compressed air pump 301 and the air pressure regulating valve 302 to each of the power supply ports 304a, 307a of the monostable multivibrator elements 304, 307 and the power supply port 311a of the rate of rotation detector 308. When the compressed air trigger pulse signal P_{a_1} shown in FIG. 3a and generated at the output port 311b of the detector 308 on every revolution of the crank shaft, is ap-

plied as a trigger signal to the control port 307b of the monostable multivibrator element 307, under such condition, an air pulse Pb_1 of a width tn_1 as shown in FIG. 3b is generated at the output port 307c of said monostable multivibrator element 307 irrespectively of the rate of rotation of the engine 309. The air pulse thus generated at the output port 307c is partially applied to the control port 304c of the monostable multivibrator element 304 as a trigger signal, whereupon the compressed air flow which has been passing from the power supply port 304a into the NOR output port 304e in said monostable multivibrator element, is directed into the OR output port 304d. The compressed air discharged from the OR output port 304d is partially supplied to the control port 304c' after restricting the flow rate by the fixed fluidic resistance 306d. By so doing, the compressed air continuously flows into the OR output port 304d even if the compressed air pulse supplied from the output port 307c of the monostable multivibrator element 307 to the control port 304c of the monostable multivibrator element 304 disappears. On the other hand, the compressed air pulse generated at the output port 307c of the monostable multivibrator element 307 is partially supplied to the power supply port 341g of the variable circuit-length device 305. The compressed air pulse thus supplied passes at the sonic velocity through the shortest distance of the passage formed by the helical groove 304e and the passages 341b of the second helical groove member 341c; the second annular groove 341d, the passage 341e, the first annular groove 341e and the passages 341a of the plunger 340j; and the helical groove 340d of the first helical groove member 340b, and is discharged from the output port 341f with a delay time as determined by the length of said passage. Here, since the total length of the passage 341a, the first annular groove 341c, the passage 341e and the second annular groove 341d (hereinafter referred to as a fixed length) is predetermined, the length of the aforesaid passage is varied by the sum of the length of that portion of the second helical groove 340e extending from the power supply port 341g to the inlet end of the passage 341b open in the second helical groove 341d (the portion indicated by M_1 in FIG. 7) and the length of that portion of the first helical groove 341d extending from the outlet end of the passage 341a open in the first annular groove 341c (the portion indicated by N_1 in FIG. 7) to the output port 341a. When the pressure introduced into the chamber 340m is 760 mmHg in terms of absolute pressure, the bellows 340n-340s are held in the most contracted state by the effects of said absolute pressure 760 mmHg and the biasing force of the spring 340y and accordingly the plunger 340j is moved in the cylinder bore 340i. Therefore, the length of the aforesaid passage varies incident to the movement of the plunger 340j. In the state shown in FIG. 7, the engine is in an idling operation and the pressure generated in the suction manifold during the idling operation of the engine is introduced into the chamber 340m. Now, when in the state of FIG. 7 the absolute pressure in the suction manifold 319 introduced into the chamber 340m through the negative pressure sending port 334 and the negative pressure introducing pipe 340z decreases gradually incident to the operation of the engine, the bellows 340n-340s move in the

direction of the arrow C_1 against the biasing force of the spring 340y, under the resilient force possessed thereby, an amount commensurating with the pressure differential between the absolute pressure of 0 mmHg in said bellows and the absolute pressure in the suction manifold 319 introduced into the chamber 340m, and accordingly the plunger 340j moves in the direction of the arrow C_1 . As a result, the points of communication between the first and second annular grooves 341c, 341d of the plunger 340j and the passages 341a, 341b, are shifted and the effective length of the variable passage becomes shorter in proportion to the amount of movement of the plunger 340j in the direction of the arrow C_1 . Thus, the pulse delay time is shortened. The relationship between the absolute pressure P_2 (mmHg) in the suction manifold 319 and the pulse delay time t_6 (mm sec) is as shown in FIG. 9. In this figure, strictly speaking, the above-mentioned relationship is represented by the stepwise solid curve K, but, the pitch of the helical grooves 340d, 340e is sufficiently made small, in practice the relationship may be considered to be approximately represented by the chain line L. Namely, the delay time t_b increases stepwise and with a certain gradient as the absolute pressure P_2 in the suction manifold 319 increases. In other words, the delay time of the compressed air flowing into the power supply port 341g and discharged from the output port 341f, on an average, is proportional to the manifold absolute pressure P_2 introduced into the chamber 340m. In FIG. 9, the reference symbol Max on the axis of ordinate indicates the point where the delay time t_b is maximum, and Min indicates the point where the delay time is minimum. The gradient of the characteristic curve of the delay time t_b with respect to the manifold absolute pressure P_2 is determined by the pitch of the helical grooves 340d, 340e of the variable circuit-length device 340. With the rate of rotation of the engine being constant, when the compressed air pulses Pc_1 , Pc_2 , Pc_3 of a width tn_1 (shown in FIG. 3b) generated at the output port 307c of the monostable multivibrator element 307 and delayed by the variable circuit-length device 340, as by the times t_1 , t_2 , t_3 as shown in FIG. 3c respectively, are applied to the control port 304b of the monostable multivibrator element 304, the compressed air flow which has been flowing into the OR output port 304d, is directed into the NOR output port 304c in either case. Therefore, compressed air pulses Pd_1 , Pe_1 , Pf_1 of width t_1 , t_2 , t_3 as shown in FIGS. 3d, 3e, 3f respectively are generated at the OR output port 304d. The width of the compressed air pulse generated at the OR output port 304d is varied by the delay time provided by the variable circuit-length device 340, i.e., the size of the engine load represented by the manifold absolute pressure.

In order to follow the high speed operation of the engine, it is necessary to increase the quantity of fuel injected during one cycle of operation of the engine to the possible extent, by reducing the pulse interval and increasing the pulse width, even though the period of the pulse is short. If an arrangement is made such that a pulse Pc_3 is generated when the delay time provided by the variable circuit-length device 340 is t_3 and longest, as shown in FIG. 3f, and the falling point of this pulse becomes equal to the rising point of the output compressed air pulse Pb_1 of the monostable multivibrator

element 307, the pulse interval will become shortest and t_{n_1} , and the pulse width will become largest and t_3 . The sum of the maximum value t_3 of pulse width and the minimum value t_{n_1} of pulse interval is the period of the pulse and this period is determined by the maximum rate of rotation of the engine. Therefore, the time which can be used for injecting the fuel can be made longest, even during the high speed operation of the engine.

At the NOR output port 304e is generated a compressed air pulse of a phase reverse to that of the air pulse generated at the OR output port 304d but this pulse is released into the atmosphere.

Where no compressed air pulses are generated at the OR output port 304d of the monostable multivibrator element 304, the fuel injected from the fuel injection nozzle 323 in the form of a jet flows entirely into a fuel receiving pipe 324 to be returned to a float chamber 328 through a fuel return pipe 326. However, when a compressed air pulse is generated at the output port 304d of the monostable multivibrator element 304, said compressed air pulse is jettisoned from the compressed air nozzle 325 and the fuel passing from the fuel injection nozzle 323 into the fuel receiving pipe 324 is deflected and atomized by said compressed air as shown in FIG. 7 and injected into the suction manifold 319 to be supplied into a cylinder 314 through the throttle valve. Thus, according to this embodiment, the relationship between the manifold pressure P_3 (mmHg) and the quantity of fuel demanded by the engine for each cycle of operation shown in FIG. 10 can be satisfied, owing to the pulse delaying characteristic of the variable circuit-length device 340 relative to the manifold pressure P (mmHg) as shown in FIG. 9. For obtaining a mixture of a desired fuel-air ratio, it is only necessary to control the ratio between the product of the suction efficiency and air density (which is proportional to the quantity of air sucked in one cycle of the engine) and the pulse width to be a certain value. In this embodiment, the fuel-air ratio is constantly controlled to be an optimum value by applying the manifold pressure into the negative pressure chamber 340m of the variable circuit-length device 340 through the negative pressure sensing port 334 as described above.

The fluidic rate of rotation detector 8 produces two of the pulse P_{4a} shown in FIG. 3a on every two revolutions of the crank shaft or each cycle of the engine. Therefore, two compressed air pulses are generated at the OR output port 304d of the monostable multivibrator element 304 in each cycle of the engine based on the pulse P_{4a} , and the width of said pulses corresponds to the size of the engine load. Particularly in the high speed, high load region of the engine, the waveform of the compressed air pulse generated at the OR output port 304d becomes close to the waveform shown in FIG. 3f, the pulse width becomes extremely wide and the pulse interval becomes extremely close to the value of t_{n_1} . Namely, the fuel injected from the fuel injection nozzle 323 for one cycle of engine is almost entirely injected into the suction manifold 319 continuously by the compressed air pulse of an extremely wide width jettisoned from the compressed air nozzle, except for a short period of time corresponding to the pulse interval, and a very small quantity of fuel injected from said fuel injection nozzle 323 during said short period of

time only is returned to the flat chamber 328 through the fuel receiving pipe 324. Particularly, in the high speed, high load region of the engine, a quantity of fuel demanded by the engine for one cycle of operation can be continuously uniformly injected into the suction manifold 319 during the period of one cycle, except for the aforesaid very short period of time. This makes it possible to use a pump of smaller capacity for a fuel injection pump 331 than the capacity of the pump required in the case when a quantity of fuel demanded by the engine is injected all at once for only a short period of time during one cycle of the engine. In addition, where the engine is a multi-cylinder engine, the quantities of fuel to be supplied to the respective cylinders can be uniformized. These advantages are particularly apparent in the high speed, high load region of the engine. Moreover, in the low speed, low load region of the engine, the fuel injection period can be shortened to t_{n_1} by shortening the pulse delay time to t_{n_1} and thereby the quantity of fuel to be injected can be minimized.

In this embodiment also, the toxic gases in the exhaust gas are oxidized and rendered harmless by the compressed air blown from an air injection nozzle 339 through a check valve 338; the fuel supply to the engine 309 is interrupted at the time of abrupt deceleration of the engine, by the operation of the valve 336; and the current supply to the fuel injection pump 331 is interrupted by the operation of the valve 337 upon failure of the compressed air pump 301, to interrupt the fuel supply to the fuel injection nozzle 323, as described previously with reference to the first embodiment.

It should also be understood that the monostable multivibrator element 304 used in this embodiment of the control system may be replaced by a bistable multivibrator element and the variable circuit-length device 340 may be inserted in the negative feed back circuit of these elements.

The fourth embodiment of the control system has the same effects as those of the first embodiment because of the construction described above. In addition, since the effective length of the passage of the variable circuit-length device 340, which determines the delay time, is varied according to the absolute pressure differential between a predetermined absolute pressure and the manifold pressure, there can be obtained such advantage that a quantity of fuel demanded by the engine can always be supplied to the engine without undergoing the influence of atmospheric pressure change, even when the engine is operated on the horizontal ground where the atmospheric pressure is 760 mmHg or in the mountains where the atmospheric pressure is lower than 760 mmHg.

Finally, the fifth embodiment of the invention will be described with reference to FIGS. 11 and 12 in which same parts or devices as those used in the first embodiment are indicated by the same reference numerals with 400 added thereto. In FIGS. 11 and 12, reference numeral 401 a compressed air pump driven from an internal combustion engine or an electric motor; 402 an air pressure regulating valve by which the discharge air pressure of said compressed air pump 401 is maintained constant; 403 a fluidic control circuit; and 404 a fluidic monostable multivibrator element having a

power supply port 404a, control ports 404b, 404c, 404c', an OR output port 404d and a NOR output port 404e. The output port 404d and control port 404c' are communicated by a positive feed back pipe 404f, and the output port 404e is opened into the atmosphere. Reference numeral 405 designates a variable circuit-length device which is of the same construction as that of the variable circuit-length device 5 shown in FIG. 1. A power supply port 405d of the device 405 is communicated with an output port 407c of a fluidic monostable multivibrator element 407 to be described later, and an output port 405e thereof is communicated with the control port 404b of the monostable multivibrator element 404.

Reference numeral 440 designates an atmospheric pressure compensating variable circuit-length device, the construction of which is similar to but slightly different from that of the variable circuit-length device 340 in the fourth embodiment as will be understood from the following description. Namely, the variable circuit-length device 440 has a first casing 440a, and a first helical groove member 440b and a second helical groove member 440c which respectively have helical grooves 440d, 440e formed in the outer peripheral surfaces thereof and axial bores 440f, 440g therein. The first and second helical groove members 440b, 440c are axially disposed in said casing 440a in side-by-side relation and their helical grooves 440d, 440e are axially independent of each other, and further their axial bores 440f, 440g form one through-hole. Reference numeral 440h designates a cylinder body having an axial cylinder bore 440i formed therein. The cylinder body 440h is closely fitted in the axial bores 440f, 440g of the helical groove members 440b, 440c. Reference numeral 440j designates a plunger which is slidably received in the cylinder bore 440i of the cylinder body 440h. Reference numeral 440k designates a second casing which is fixed to the open end of the first casing 440a by bolts 440l and defines a chamber 440m therein. Reference numerals 440n, 440o, 440p, 440q, 440r, 440s designate bellows each made, for example, of a resilient metallic material and having the interior thereof maintained at the absolute pressure of 0 mmHg. These bellows are connected with each other and disposed in the chamber 440m. One of the bellows 440n is connected at its end 440t to the plunger 440j and another one of them 440s is formed with a conical recess 440u at one end thereof, in which is received one end of an adjusting screw 440v. The adjusting screw 440v is threadably screwed into an internally threaded cylindrical portion 440w of the casing 440k. Reference numeral 440x designates a protective cap fitted over the cylindrical portion 440w in threadable engagement with external threads formed in the outer periphery of said portion 440w. Reference numeral 440y designates a spring disposed between the outer end of the cylinder body 440h and the end 440t of the bellows 440n, to surround the plunger 440j. Reference numeral 440z designates an atmospheric pressure introducing pipe having one end opened into the chamber 440m and the other end opened into the atmosphere. An arrangement is made such that when the chamber 440m is maintained at a pressure of 760 mmHg, the bellows 440n-440s the interior of which is maintained at the absolute pressure of 0 mmHg, are

held in the most contacted state by the atmospheric pressure of 760 mmHg and the biasing force of the spring 440y overcoming the resilient forces of said bellows, as shown in FIG. 11.

FIG. 12 is a transverse cross-sectional view of the first helical groove member 440b and the second helical groove member 440c in a plane perpendicular to the axes thereof. As seen, the first and second helical groove members respectively have a plurality of radial passages 441a, 441b extending from the bottom of the helical grooves 440d, 440e through the bodies of said first and second helical groove members and the wall of the cylinder body 440h into the cylinder bore 440i, over the entire length of said helical grooves. The plunger 440j has axially spaced first and second annular grooves 441c, 441d formed in the outer peripheral surface thereof for communication with the passage 441a communicating with the helical groove 440d and the passage 441b communicating with the helical groove 440a, respectively. These annular grooves 441c, 441d are communicated with each other by a passage 441e formed in the plunger 440j. Reference numeral 441f designates a power supply port of the variable circuit-length device 440, which is communicated at one end with the first helical groove 440d at the starting end of the latter, and the other end with an output port 407c of a fluidic monostable multivibrator element 407 to be described later. Reference numeral 441g designates an output port of the device 440, which is communicated at one end with the terminating end of the second helical groove 440e and also with the control port 404c of the monostable multivibrator element 404. Reference numerals 406a, 406b, 406c, 406d designate fixed fluidic resistances each consisting, for example, of an orifice. Reference numeral 407 designates a fluidic monostable multivibrator element having a power supply port 407a, a control port 407b and output ports 407c, 407d. The output port 407c is communicated with the power supply port 441g of the variable circuit-length device 440 and the other output port 407d is opened into the atmosphere. Reference numeral 408 designates a fluidic rate of rotation detector which generates air pulse signals and the construction of which is identical with that of the detector 8 shown in FIG. 1. Namely, the detector 408 is so constructed as to generate one pulse P_{a2} shown in FIG. 13a on every revolution of the crank shaft. An output port 411b of a member 411 is communicated with the control port 407b of the monostable multivibrator element 407. A predetermined pressure of compressed air is supplied by the compressed air pump 401 and the air pressure regulating valve 402 to each of the power supply ports 404a, 407a of the monostable multivibrator elements 404, 407 and a power supply port 411a of the detector 408. The pressure ratio of the compressed air supplied to the respective ports is adjusted by the fixed fluidic resistances 406a, 406b, 406c. Reference character A_5 generally indicates the engine 409 and devices associated therewith, and the construction of the portion A_5 is exactly the same as that of A_1 shown in FIG. 1. A compressed air nozzle 425 is communicated with the OR output port 404d of the monostable multivibrator element 404 and a negative pressure sensing port 434 is communicated with a negative pressure introducing port 405n of the variable circuit-length device 405.

A plunger 405f of the variable circuit-length device 405 and a throttle valve 420 are operatively connected with each other by a link mechanism through a switching device 442 which is operated on a special occasion, so that said plunger 405f may be operated on a special occasion according to the degree of opening of said throttle valve 420. The functions of valves 436, 437 are exactly the same as those of the valves 36, 37 shown in FIG. 1.

The operation of this embodiment will be described hereunder: As stated above, a predetermined pressure of compressed air is constantly supplied by the compressed air pump 401 and the air pressure regulating valve 402 to each of the power supply ports 404a, 407a of the monostable multivibrator elements 404, 407 and the power supply port 411a of the rate of rotation detector 408. When the compressed air trigger pulse signal P_{a2} shown in FIG. 13a and generated at the output port 411b of the detector 408, is applied as a trigger signal to the control port 407b of the monostable multivibrator element 407 under such condition, a compressed air pulse P_{b2} of a width t_{n2} is generated at the output port 407c of said element 7 irrespectively of the rate of rotation of the engine 409. The air pulse thus generated at the output port 407c is partially applied as a trigger pulse to the control port 404c of the monostable multivibrator element 404 through the atmospheric pressure compensating variable circuit-length device 440, whereupon the compressed air passing from the power supply port 404a into the NOR output port 404e of the monostable multivibrator element 404 is directed into the OR output port 404d. The compressed air discharged from the OR output port 404d is partially supplied to the control port 404c' through the pipe 404f after restricting the flow rate by the fluidic resistance 406d. By so doing, the compressed air continuously flows into the OR output port 404d even when the compressed air pulse supplied from the output port 407c of the monostable multivibrator element 407 to the control port 404c of the monostable multivibrator element 404 disappears. On the other hand, the compressed air pulse generated at the output port 407c of the monostable multivibrator element 407 is partially supplied to the power supply port 405d of the variable circuit-length device 405. The compressed air pulse thus supplied passes at the sonic velocity through the passage formed by a helical groove 405b, an annular port 405g, a passage 405i, a port 405h and an elongate groove 405c, and reaches the output port 405e with a delay time as determined by the length of said passage. Since the length of the passage 405i is predetermined, the delay time is varied by the length of that portion of the helical groove 405b from the power supply port 405d to the annular port 405g (hereinafter referred to as effective length). The effective length of the variable circuit-length device 405 is varied in the following manner: Namely, the plunger 405f is moved in proportion to the magnitude of the manifold vacuum pressure introduced into a negative pressure chamber 405l. Now, when the manifold pressure is introduced into the negative pressure chamber 405l through the negative pressure sensing port 434 and the negative pressure introducing pipe 405n, and is lower than the absolute pressure of 760 mmHg, a diaphragm 405k is attracted toward the negative pressure chamber 405l under suction against the biasing force of a spring 405q,

and accordingly the plunger 405f is moved in the direction of the arrow B₄. The amount of movement of the plunger 405f is proportional to the pressure differential between the manifold pressure introduced into the negative pressure chamber 405l and the atmospheric pressure. As a result, the annular port 405g of the plunger 405f is shifted to a position to communicate with the helical groove 405b. Therefore, it will be understood that the effective length mentioned above and hence the delay time gradually becomes shorter as the negative pressure in the negative pressure chamber 405l gradually becomes larger. Conversely, the effective length and hence the delay time gradually becomes longer as the pressure in the negative pressure chamber 405l gradually approaches the atmospheric pressure. The relationship between the manifold pressure P_1 (mmHg) and the pulse delay time t_a (mm sec) is as shown in FIG. 4. In FIG. 4 a curve indicated by character E is the characteristic curve in the case when the engine is operated on the horizontal ground where the atmospheric pressure is 760 mmHg, and the pitch of the helical groove 405b is made small at the end portion remote from the power supply port 405d so that the gradient of the curve E may be relatively gentle when the manifold pressure P_1 is in the range of 400 to 700 mmHg but may be relatively steep when said pressure P_1 exceeds 700 mmHg. A curve indicated by character D is the characteristic curve in the case when the engine is operated on high ground such as in the mountains where the atmospheric pressure is 660 mmHg, and is the curve E displaced to the left parallel to the axis of abscissa by a distance corresponding to 100 mmHg. The marking Max on the axis of ordinate indicates the point where the delay time is maximum and Min indicates the point where the delay time is minimum.

The atmospheric pressure compensating variable circuit-length device 440 operates as follows: When compressed air is supplied to the power supply port 441f, it passes at the sonic velocity through the shortest distance of the passage formed by the helical groove 440d and the passages 441a of the first helical groove member 440b, the first annular groove 441c and the passage 441e of the plunger 440j, the second annular passage 441d, the passages 441b and the second helical groove 441d of the second helical groove member 440c, and is discharged into the output port 441g with a delay time as determined by the length of said passage. Here, since the total length of the passages 441a, 441b, the first annular groove 441c, the passage first e and the second annular groove 441d (hereinafter referred to as fixed length) is predetermined, the length of the above-mentioned passage is varied by the sum of the length of that portion of the first annular groove 440d extending from the power supply port 441f to the inlet end of the passage 441a open in the first annular groove 441c (the portion indicated by M_2 in FIG. 11) and the length of that portion of the second helical groove 441e extending from the outlet end of the passage 441b open in the second annular groove 441d (the portion indicated by N_2 in FIG. 11) to the output port 441g, (said sum of the lengths being hereinafter referred to as variable length). When the automobile is running on the horizontal ground where the atmospheric pressure is, for example, 760 mmHg in terms of absolute pressure,

the bellows 440n-440s are held in the most contracted state as shown in FIG. 11 under the effect of said atmospheric pressure and the biasing force of the spring 440y, and hence the plunger 440j is at the lower end of its stroke as shown in FIG. 11. Therefore, the length of the aforesaid passage (the fixed length + the variable length) is shortest and the delay time of compressed air pulse is also shortest. Now, when the automobile travels on high ground such as in the mountains, the atmospheric pressure becomes lower as the level of the ground rises, and the absolute atmospheric pressure introduced into the chamber 440m becomes smaller accordingly. Therefore, the bellows 440n-440s expand under their own resilient forces in the direction of the arrow C₂ in FIG. 11 against the biasing force of the spring 440y, according to the pressure differential between the absolute pressure of 0 mmHg therein and the absolute atmospheric pressure introduced into the chamber 440m, and thus the plunger 440j also moves in the direction of the arrow C₂. As a result, the points of communication between the first and second annular grooves 441c, 441d of the plunger 440j and the passages 441a, 441b are shifted and the aforesaid variable length increases in proportion to the amount of movement of the plunger 440j, whereby the pulse delay time becomes longer. The relationship between the atmospheric pressure P₄ (mmHg) and the delay time t_c (mm sec) incident to movement of the plunger 440j in the direction of the arrow C₂ is as shown in FIG. 14. In this figure, strictly speaking the above-mentioned relationship is represented by the stepwise solid curve M, but, the pitch of the helical grooves 440d, 440e is sufficiently made small, in practice the relationship may be considered to be approximately represented by the chain line N. Namely, the delay time t_c becomes shorter stepwise with a certain gradient as the atmospheric pressure P₄ increases. In other words, the delay time of the compressed air pulse flowing into the power supply port 441f and discharged from the output port 441g, on an average, is proportional with a negative constant of proportion, to the atmospheric pressure P₄ introduced into the chamber 440m. In FIG. 14, the marking Max on the axis of ordinate indicates the point where the delay time t_c is maximum, and Min indicated the point where the delay time t_c is minimum. The gradient of the characteristic curve of the delay time t_c with respect to the atmospheric pressure P₄ is determined by the pitch of the helical grooves 440d, 440e of the variable circuit-length device 440. With the rate of rotation of the engine being constant, when the compressed air pulses (shown in FIG. 13b) generated at the output port 407c of the monostable multivibrator element 407 and delayed by the variable circuit-length device 405, for instance, by a time t₄ as shown in FIG. 13d and by the atmospheric pressure compensating variable circuit-length device 440, for instance by a time t₅ as shown in FIG. 13c, respectively, are applied to the control ports 404b, 404c of the monostable multivibrator element 404, compressed air is discharged from the OR output port 404d with the delay time t₅ and the discharge of compressed air is interrupted with the delay time t₄ with respect to the air pulse generated at the output port 407c of the monostable multivibrator element 407. Namely, a compressed air pulse having a width of t₄-t₅ as shown in FIG. 13e is generated at the

OR output port 404d of the monostable multivibrator element 404. Therefore, the width of the compressed air pulse generated at the OR output port 404d is varied by the balance of the delay time t_a provided by the variable circuit-length device 405 and the delay time t_c provided by the variable circuit-length device 440.

The minimum value of the pulse interval of the compressed air pulse generated at the OR output port 404d can be decreased to t_{n2} as shown in FIG. 13f, which is the width of the output compressed air pulse P_{b2} of the monostable multivibrator element 407 shown in FIG. 13b. At the NOR output port 404e is generated a compressed air pulse of a phase reverse to that of the pulse generated at the OR output port 404d, and this pulse is released into the atmosphere.

The atmospheric pressure compensating variable circuit-length device 440 is provided for the following reason: FIG. 15 shows the relationship between the internal pressure P₅ (mmHg) of the suction manifold 419 and the quantity Q of fuel demanded by the engine for each cycle of operation. A curve G represents the case when the engine is operated at the atmospheric pressure of 760 mmHg and a curve H represents the case when the engine is operated on high ground where the atmospheric pressure is as low as, for instance, 660 mmHg. As may be apparent from FIG. 15, a change in quantity of fuel demanded by the engine, with changing atmospheric pressure, can be compensated by incorporating the variable circuit-length device 440 in the fluidic circuit and reducing the width of the compressed air pulse generated at the OR output port 404d of the monostable multivibrator element 404 by an amount proportional to the amount of lowering of the atmospheric pressure, as described above.

Where no compressed air pulses are generated at the OR output port 404d of the monostable multivibrator element 404, the fuel injected from the fuel injection nozzle 423 in the form of a jet flows entirely into a fuel receiving pipe 424 to be returned to a float chamber 428 through a fuel return pipe 426. However, when a compressed air pulse is generated at the output port 404d, said compressed air pulse is jetted from the compressed air nozzle 425 and the fuel passing from the fuel injection nozzle 423 into the fuel receiving pipe 424 is deflected and atomized by said compressed air as shown in FIG. 11 and injected into the suction manifold 419 to be supplied into a cylinder 414 through the throttle valve. For obtaining a mixture of a desired fuel-air ratio, it is only necessary to control the ratio between the product of the suction efficiency and air density (which is proportional to the quantity of air sucked in one cycle of the engine) and the pulse width to be a certain value. In this embodiment, as described above, the pulse width is determined by the balance of the delay time t_a provided by the variable circuit-length device 405 and the delay time t_c provided by the atmospheric pressure compensating variable circuit-length device 440 and thereby the fuel-air ratio is controlled to be an optimum value at all times. The plunger 405f is operated by the link mechanism 435, including the switching device 442, according to the degree of opening of the throttle valve 420, on the occasion when it becomes necessary to increase the quantity of fuel to be supplied, particularly at the time of acceleration.

The fluidic rate of rotation detector 8 produces two of the pulse P_{a_2} shown in FIG. 13a on every two revolutions of the crank shaft or each cycle of the engine. Therefore, two compressed air pulses are generated at the OR output port 404d of the monostable multivibrator element 404 in each cycle of the engine based on the pulse P_{a_2} , and the width of said pulses corresponds to the size of the engine load. Particularly, in the high speed, high load region of the engine on the horizontal ground, the waveform of the compressed air pulse generated at the OR output port 404d becomes close to the waveform shown in FIG. 13f, the pulse width becomes extremely wide and the pulse interval becomes extremely close to the value of tn_2 . Namely, the fuel injected from the fuel injection nozzle 423 for one cycle of engine is almost entirely injected into the suction manifold 419 continuously by the compressed air pulse of an extremely wide width jetted from the compressed air nozzle, except for a short period of time corresponding to the pulse interval, and a very small quantity of fuel injected from said fuel injection nozzle 423 during said short period of time only is returned to the float chamber 428 through the fuel receiving pipe 424. Particularly, in the high speed, high load region of the engine on the horizontal ground, a quantity of fuel demanded by the engine for one cycle of operation can be continuously uniformly injected into the suction manifold 419 during the period of one cycle, except for the aforesaid very short period of time. This makes it possible to use a pump of smaller capacity for a fuel injection pump 431 than the capacity of the pump required in the case when a quantity of fuel demanded by the engine is injected all at once for only a short period of time during one cycle of the engine. In addition, where the engine is a multi-cylinder engine, the quantities of fuel to be injected to the respective cylinders can be uniformized. Moreover, in the low speed, low load region of the engine, the fuel injection period can be shortened to tn_2 by shortening the pulse delay time to tn_2 and thereby the quantity of fuel to be injected can be minimized.

In this embodiment also, the toxic gases in the exhaust gas are oxidized and rendered harmless by the compressed air blown from an air injection nozzle 439 through a check valve 438; the fuel supply to the engine 409 is interrupted at the time of abrupt deceleration of the engine, by the operation of the valve 436; and the current supply to the fuel injection pump 431 is interrupted by the operation of the valve 437 upon fuel supply to the fuel injection nozzle 423, as described previously with reference to the first embodiment.

It should be understood that, while in the embodiments described herein, compressed air is used as operating fluid, a liquid such as water or gasoline may also be used instead of the compressed air.

It should also be understood that, while the present invention has been described herein as applied to a single cylinder engine, in case of a multi-cylinder engine fuel to be injected to each cylinder can be properly controlled by providing the fuel injection nozzle 23, the fuel receiving pipe 24, the compressed air nozzle 25, etc. of the construction shown in FIG. 1, for each cylinder. Furthermore, in the embodiments described herein the abrupt deceleration of the engine 9, 109, 209, 309 or 409 is detected by the valve 36, 136, 236,

336 or 436 by making use of the manifold vacuum pressure from the negative pressure sensing port 34, 134, 234, 334, or 434, but it can be detected by the degree of opening of the throttle valve 20, 120, 220, 320, or 420. Namely, the power supply to the fuel injection pump 31, 131, 231, 331 or 431 can be interrupted by detecting the degree of opening of said throttle valve.

It is also to be understood that the fluidic monostable multivibrator element 4, 104, 204, 304 or 404 may be replaced by a bistable multivibrator element.

The fifth embodiment of the control system has the same effects as those of the first embodiment because of the construction described above. In addition, since the quantity of fuel injected is regulated by a change in the atmospheric pressure, there can be obtained such advantage that a quantity of fuel demanded by the engine can always be supplied to the engine without undergoing the influence of atmospheric pressure change, on the horizontal ground where the atmospheric pressure is 760 mmHg as well as on high ground where the atmospheric pressure is below 760 mmHg.

What is claimed is:

1. A control system for a fuel injection device of internal combustion engines, comprising trigger pulse generating means for generating a trigger pulse in synchronism with the rotation of an internal combustion engine, variable circuit-length means by which the length of a fluid passage can be varied according to the load on said engine and fluidic control circuit for generating a fluidic pulse of a variable width and a variable number in cooperation with said variable circuit-length means and said trigger pulse generating means, the trigger pulse generated by said trigger pulse generating means being applied to said fluidic control circuit and said variable circuit-length means, whereby a fluidic pulse is generated by said fluidic control circuit, which is used for controlling the quantity of fuel supplied to said engine.

2. A control system for a fuel injection device of internal combustion engines, according to claim 1, wherein said fluidic control circuit includes a multivibrator element, and said variable circuit-length means is inserted in a negative feed back circuit of said element or in a circuit by which a pipe for applying the trigger pulse to a first control port of said element therethrough communicates with a second control port of said element.

3. A control system for a fuel injection device of internal combustion engines, according to claim 2, wherein said trigger pulse generating means includes a rate of rotation detecting unit adapted to generate a pulse by intermittently interrupting a fluid passage and a monostable multivibrator element for shaping the output pulse of said rate of rotation detecting unit.

4. A control system for a fuel injection device of internal combustion engines, according to claim 3, wherein said monostable multivibrator element included in the trigger pulse generating means is a one-shot monostable multivibrator element and said multivibrator element included in the fluidic control circuit is a bistable multivibrator element.

5. A control system for a fuel injection device of internal combustion engines, according to claim 3, wherein said monostable multivibrator element included in the trigger pulse generating means is a one-

shot monostable multivibrator element and said multivibrator element included in the fluidic control circuit is an OR-NOR monostable multivibrator element.

6. A control system for a fuel injection device of internal combustion engines, according to claim 4, wherein said fluidic control circuit further includes a monostable multivibrator element for amplifying the output pulse of said bistable multivibrator element.

7. A control system for a fuel injection device of internal combustion engine, comprising trigger pulse generating means for generating a trigger pulse in synchronism with the rotation of an internal combustion engine, first variable circuit-length means by which the length of a fluid passage can be varied according to the load on the engine, second variable cir-

15

cuit-length means by which the length of a fluid passage can be varied according to the atmospheric pressure, and fluidic control circuit for generating a fluidic pulse of a variable width and a variable number in cooperation with said first and second variable circuit-length means and said trigger pulse generating means, the trigger pulses generated by said trigger pulse generating means being applied, one to said fluidic control circuit through said second variable circuit-length means and the other one to said fluidic control circuit and said first variable circuit-length means, whereby a fluidic pulse is generated by said fluidic control circuit, which is used for controlling the quantity of fuel supplied to said engine.
